UNITED STATES PATENT OFFICE.

LUCIEN A. MARSH, OF MILL VALLEY, CALIFORNIA.

GAME BOARD.

Application filed March 26, 1923. Serial No. 627,880.

To all whom it may concern:

Be it known that I, LUCIEN A. MARSH, a citizen of the United States, residing at Mill Valley, county of Marin, and State of California, have invented new and useful Improvements in Game Boards, of which the following is a specification.

This invention relates to a game board designed to expedite the playing of the oriental game commonly known as Mah jongg. This game is played with a number of flat oblong playing pieces bearing characters or legends which are factors in the game. During the course of the game, each player accumulates a group of playing pieces or tiles, which is termed the player's "hand".

To permit each player to arrange the tiles constituting his hand on edge in a position concealing their characterized faces from the other players but permitting him to readily refer thereto at each play, elongated devices termed racks were designed. These racks are formed angular in cross-section and during the game are placed on the game board to accommodate the tiles and support them with their characterized faces at an angle to the vertical to permit convenient reference thereto.

These racks have not proven entirely satisfactory for the reason that when the game is not in use they easily become broken, misplaced and lost.

It is the principal object of the present invention to provide a generally improved game board which is particularly adapted for playing the game Mah jongg and which is provided with improved means for accommodating the auxiliary playing elements of the game to prevent them from being broken or misplaced when the game is not in use.

In carrying out this object I provide a game board arranged with receptacles at its sides for the reception of playing elements of the game. Above these receptacles the board is recessed to accommodate racks which may be yieldably held in the recesses in a protected position to serve as a cover for the receptacles and to insure that the racks will not become broken or misplaced.

One form which the invention may assume is exemplified in the following description and illustrated by way of example in the accompanying drawings, in which:

Fig. 1 is a perspective view of a game board embodying the invention.

Fig. 2 is a fragmentary view in section taken on line 2-2 of Fig. 1.

Fig. 3 is a fragmentary view in elevation and section showing the means for yieldably holding the racks in place.

Referring more particularly to the accompanying drawings, 10 indicates a rectangular game board having a playing surface 11 and sides 12. This board may be constructed as an auxiliary table top or fitted with folding or rigid supporting legs as desired.

Each side of the table is formed with an extension 14 of substantially rectangular cross section as shown in Fig. 2. These extensions are formed with pockets 15 which may be used to contain counters and other playing elements of the game so that they will be convenient to each player.

The top of each extension 14 is longitudinally recessed as at 14^a to accommodate an elongated rack 16. These racks are each formed of a side portion 17 and a base portion 18 which are formed at right angles to each other. The face of the rack is grooved at 19 to support the tiles at an angle to the vertical when the rack is arranged on the board with the base portion 18 resting on the playing surface.

The recesses 14^a in the extensions 14 are of substantially the same dimensions as the racks to permit the latter to be inverted and nested therein as shown in Fig. 2. The front edge of each extension 14 is grooved along the edge of the recess to accommodate the edge of the side portion 17 of the rack.

Each rack is fitted at one end with a lug 20 which is insertible in a socket 21 at the end of the recess 14^a. The other end of each rack is fitted with a spring latch 22 which is adapted to engage a socket 23 in the adjacent end of the recess 14^a. By the means just mentioned, the racks may be yieldably held in position in the recesses 14^a and will constitute covers for the pockets 15.

During the period that the game board is in use, the racks are positioned on the table to support the tiles constituting the players' hands as described. The pockets 15 are therefore uncovered and the players will have access to any of the articles contained therein.

When the table is not in use the racks may be nested in an inverted position in the recesses and yieldably held therein to cover

the pockets 15 and to insure that the racks will not be broken or misplaced. In this position the surfaces of the racks will be flush with the surfaces of the extension 15 and will not detract from the appearance of the game board.

From the foregoing it is obvious that a very desirable game board has been provided.

10 While I have disclosed the preferred form of my device, it is understood that various changes in its construction may be made without departing from the invention as defined in the appended claims.

15 Having thus described my invention, what I claim and desire to secure by Letters Patent is:—

1. In combination with a game board having a rectangular playing surface, a plurality of racks, said game board having a recess formed at each side thereof for removably receiving one of said racks and yieldably holding it in a protected position whereby said racks may be disposed in said recesses with their exposed surfaces substantially flush with the adjacent surfaces of the game board or removed from the said recesses for use.

2. In combination with a game board having a rectangular playing surface, a plurality of elongated racks, the upper marginal edge of each side of said game board being formed with a recess wherein one of said racks may be yieldably held in protected position with its exposed surface substantially flush with the adjacent surfaces of the game board whereby said racks may be disposed in protected position in said recesses or removed from said recesses for use.

3. In combination with a game board having a rectangular playing surface, a plurality of elongated racks, the upper marginal

edge of each side of said game board being formed with a recess of substantially the same dimensions as one of the racks whereby said racks may be disposed in protected position in said recesses with their exposed surfaces flush with the adjacent surfaces of the board or removed from said recesses for use, and means for yieldably holding said racks in said recesses.

4. In combination with a game board having a rectangular playing surface, a plurality of elongated racks, said game board having pockets formed in each side thereof, the upper marginal edge of each side of the game board being formed with a recess of substantially the same dimensions as a rack for receiving and supporting a rack, said recesses being formed above said pockets whereby said racks may be disposed in a protected position in said recesses with their exposed surfaces flush with the adjacent surfaces of the game board, and serving as closures for said pockets, or removed from said recesses for use.

5. In combination with a game board having a rectangular playing surface, a plurality of elongated racks, extensions at each side of the game board, each of said extensions having pockets and a recess thereabove formed therein, the recess in each extension being formed at the upper marginal edge thereof and being of substantially the same dimensions as a rack for receiving and supporting the same with its exposed surfaces flush with the adjacent surfaces of the extension whereby the racks may be disposed in protected position in said recesses and serve as closures for said pockets, said racks being yieldably held in said recesses where by they may be removed for use.

LUCIEN A. MARSH,
